US0D1114356S

(12) United States Design Patent (10) Patent No.: US D1,114,356 S
(45) Date of Patent: * Feb. 17, 2026

(54) MOUTHGUARD

(71) Applicant: SYZMIK Sports, LLC, Hunt Valley, MD (US)

(72) Inventors: Nathan Dau, Palmyra, VA (US); Christopher Gregg Perra, Kansas City, MO (US)

(73) Assignee: SYZMIK Sports, LLC, Timonium, MD (US)

() Term: 15 Years

(21) Appl. No.: 29/918,567

(22) Filed: Nov. 28, 2023

(51) LOC (15) Cl. 29-02

(52) U.S. Cl.

USPC D29/108

(58) Field of Classification Search

USPC D29/100, 105, 106, 108, 122; D24/108-110.5, 156, 176, 181
